Attorneys

UNITED STATES PATENT OFFICE.

ADOLPH SPECHT, OF QUINCY, ILLINOIS, ASSIGNOR TO GEM CITY STOVE MANUFACTURING COMPANY, OF QUINCY, ILLINOIS.

DAMPER.

Application filed July 2, 1923. Serial No. 649,057.

To all whom it may concern:

Be it known that I, ADOLPH SPECHT, a citizen of the United States, residing at Quincy, in the county of Adams and State 5 of Illinois, have invented certain new and useful Improvements in Dampers; and I do hereby declare the following to be a full, clear, and exact description of the invention, such as will enable others skilled in the art 10 to which it appertains to make and use the same.

The present invention relates to air inlet dampers for stoves, furnaces and other heaters, and aims to provide a novel damper 15 construction for the ashpit door or other portion of a stove or heater, which serves as a draft regulator or register, spark arrester and an ornamental symmetrical panel.

Another object of the invention is to provide a damper device of novel construction 20 for obtaining a positive control and regulation of the draft, and the damper being of such construction as to combine therein a draft register, spark arrester and ornamental panel presenting the same symmetrical appearance in the different positions of the damper.

It is also an object of the invention to provide a damper construction of the kind indicated which is simple and comparatively 30 cheap in construction and manufacture, and which is practical and efficient in use.

With the foregoing and other objects in view, which will be apparent as the description proceeds, the invention resides in the construction and arrangement of parts, as hereinafter described and claimed, it being understood that changes can be made within the scope of what is claimed, without departing from the spirit of the invention.

The invention is illustrated in the accompanying drawing, wherein—

Fig. 1 is a front view of an ashpit door 45 of a stove showing the damper in closed position.

Fig. 2 is a fragmentary rear view of the door showing the damper open one-half way.

Figs. 3 and 4 are vertical sections on the 50 respective lines 3—3 and 4—4 of Fig. 1.

The damper, as shown, is carried by the ashpit door 7 of a stove, although it can be provided on some other door or a wall of the stove or heater where the air is admitted.

55 The door or wall 7 has a substantially semi-

circular opening 8 for the admission of air, and said opening is located near the upper edge of said door or wall, above the horizontal center line of the door, whereby the lower portion of the door is imperforate to 60 prevent the ashes from falling through the lower portion of the door, which frequently happens when the draft openings extend to the lower portion of the door.

The damper proper, indicated at 9, is of 65 circular contour, and is of dished or convexed form, with its edge turned or directed rearwardly to abut the outer or forward face of the door 7, said damper being located at the outer side of the door. The edge or 70 rim of the damper extends above the upper curved edge of the opening 8, and said opening is of slightly smaller size than one-half of the damper 9, whereby the upper half of the damper surrounds said opening. 75

The damper is pivotally connected with the door or wall 7 for rotary motion, and the damper has a central rearwardly or inwardly extending boss 10 provided with a central aperture receiving a pivot spindle 80 or pintle 11 which engages through the door 7 so as to be anchored to said door. The door 7 has an upstanding portion 12 above the spindle 11 at the lower edge of the opening 8 for the contact of the boss 10 with the door completely around said spindle. The damper 9 is provided at the outer or forward side of the boss 10 with a depression or recess 13 in which a cup or 85 spring socket 14 is seated, the spindle 11 projecting centrally through said cup or socket and having a head or knob 16 at its outer or forward end over which a sheet metal cap 15 is fitted. The cap 15 is slideable in the cup or socket 14 and has an in- 90 struck corrugation 17 engaging in an annular groove provided in the head or knob 16. A coiled expansion spring 18 surrounds the spindle 11 and is confined between the cup 14 and head or knob 16 within the 95 socket or recess of said cup, whereby the cup or member 14 is pressed inwardly or rearwardly by the spring, thereby holding the damper 9 under tension against the door 7, and retaining the damper in any angular 100 position to which it is turned.

The damper 9 is provided with a diametrical partition or division flange 19 at the inner or rear side thereof having its ends united with the rim or margin of the damper 110

and having the intermediate portion merging into the boss 10, and the edge of the partition or flange 19 is flush with the edge of the damper so that said partition abuts or contacts with the face of the door. The partition or flange 19 divides the damper into two halves, and one-half has the apertures or perforations 20 providing a grated air inlet opening, while the other half of the 10 damper is imperforate but is provided with depressions 21 resembling the apertures 20, and giving the outer side or surface of the damper a symmetrical appearance throughout the area thereof. The damper is thus of 15 ornamental design and will have the same symmetrical appearance in any position thereof. The apertures 20 and depressions 21 give an outstanding design to the damper which is nickle-plated or otherwise finished 20 so that the damper provides a circular panel for the door.

The damper has an outstanding finger piece 22, preferably near one end of the partition 19, for convenience in turning the 25 damper.

The door 7 has an outstanding stop lug 23, and the rim of the damper has outstanding lugs 24 and 25 to contact with the lug 23, so as to limit the turning movement of 30 the damper when moved to open and closed positions.

In order to regulate the draft, the damper is turned about the pivot. When the damper is turned to move the lug 24 against the lug 35 23, as seen in Fig. 1, the closed or imperforate half of the damper is disposed across the opening, thereby closing said opening, and shutting off the inlet of air, the partition or flange 19 contacting with the door 40 under the opening 8 and the upper half of the margin or rim of the damper contacting with the door above the opening 8, in order that said partition 19 and upper half of the damper rim completely surround the opening 45 to prevent the inflow of air. By turning the damper half way around, to bring the lug 25 against the lug 23, the open or perforated half of the damper is disposed across the opening 8, thereby admitting the full amount of air through the openings. The opening of the damper is grated, thereby providing a draft register, as well as a 50 spark arrester, the bars or grate extending across the opening of the damper serving to arrest hot ashes or lumps of burning coal or fuel which tend to fly through the openings. The damper can be turned to intermediate 55 positions for regulating the flow of air, and in any position of the damper between extreme closed and open positions, the partition or flange 19 extends across the opening 8, radially of said opening, with the lower portion of said partition contacting with the

door 7 below said opening, so that the half 65 of the damper which is imperforate will close a portion of the opening 8, such as at the left of the partition 19 in Fig. 2. In other words, the partition or flange 19 prevents the flow of air within the damper itself between the imperforate and open 70 halves of the damper, and the imperforate portion or half of the damper will close that portion of the opening 8 across which the imperforate portion of the damper extends, 75 in any position of the damper.

Having thus described the invention, what is claimed as new is:—

1. A damper construction comprising a wall having an opening, and a dished damper pivoted centrally to said wall and having its edge abutting said wall, the damper having a diametrical partition abutting said wall, the damper being imperforate at one side of said partition to extend across and close said opening and being open at the opposite side of said partition to register with the first named opening.

2. A damper construction comprising a wall having an opening, and a dished damper pivoted centrally to said wall below said opening and having its edge directed toward and abutting said wall, the damper having a diametrical partition abutting said wall and dividing the damper into halves, one half of the damper being imperforate to extend across and close said opening and the other half of the damper having a grated opening to register with the first named opening.

3. A damper construction comprising a wall having an opening, a dished damper having its edge directed toward and abutting said wall, the damper having a central boss directed toward and abutting said wall and having a diametrical partition united with said boss and edge portion of the damper and abutting said wall, said partition dividing the damper into halves, one half of the damper being imperforate and the other half having a grated opening, a spindle engaging the wall and extending through said boss to mount the damper for rotation on the wall, and spring means on the spindle for pressing the edge and partition of the damper against the wall, the imperforate half of the damper being adapted to extend across and close the first named opening and grated opening of the damper being adapted to register with the first named opening.

In testimony whereof I have signed my name to this specification in the presence of two subscribing witnesses.

ADOLPH SPECHT.
